UNITED STATES PATENT OFFICE.

LUCIEN LAVOISIER, OF PARIS, FRANCE.

IGNITION-PLUG FOR INTERNAL-COMBUSTION ENGINES.

1,327,482.

Specification of Letters Patent.

Patented Jan. 6, 1920.

Application filed January 21, 1918. Serial No. 213,015.

To all whom it may concern:

Be it known that I, LUCIEN LAVOISIER, a citizen of the Republic of France, residing at Paris, 14 ter Rue du Colonel Oudot, Seine Department, in the Republic of France, engineer, have invented certain new and useful Improvements in Ignition-Plugs for Internal-Combustion Engines, of which the following is a specification.

10 My invention has for its object an ignition plug for internal combustion motors which differs essentially from ordinary ignition plugs by its central rod or electrode being bored and provided with apertures 15 in such a way as to allow the surrounding air entering it up to its inner end. This arrangement has for effect to provide for effective cooling of the central electrode and of the whole center part of the body of the 20 plug, thus resulting in extending the duration of its use and in increasing the security of working.

One way of carrying out my improved ignition plug is shown in the accompanying 25 drawing by way of example, in a sectional view.

1 designates a threaded bush adapted to be screwed into the wall of the cylinder of the engine and made with a flared seat 2. 30 The insulating member 3 which surrounds the central electrode is made with a double cone shaped strengthened portion and is clamped between said seat 2 and an externally threaded clamping ring 4 adapted 35 to be screwed into the aperture of the bush 1, its inner conical surface bearing upon the exterior cone shaped portion of the strengthened part of the insulator 3. This arrangement will secure perfect tightness of 40 the device.

The central electrode consists of a bored rod 5 closed at its inner end, said inner end being formed with an inverted dished portion or flange 6 extending up to a short 45 distance from the inside of the inner end of the bush 1.

The insulated part 3 is secured on the rod 5 between a shoulder 7 formed by said dished portion of the rod and a nut 8 with 50 a washer interposed between the parts to prevent unscrewing, or without any washer.

The portion of the electrode situate above the nut 8 has a number of holes 9 drilled through it so as to reduce its weight and to permit the surrounding air of circulating 55 freely through said electrode.

The different parts of the ignition plug are sized and shaped so as to reduce as much as possible the masses of the metal parts.

60 The outer diameter of the dished portion 6 is slightly smaller than the smallest inner diameter of the bush 1 so as to allow the electrode of being removed and of being replaced without unscrewing the bush 1 65 from the engine.

70 The aforesaid arrangements make the construction of the ignition plug simple, strong and easy to take to pieces; the center portion of the ignition plug is cooled to a perfectly reliable extent, and the fixedness of the insulating member and its perfect tightness are in the same time secured in a most reliable and lasting manner.

75 In the example described and shown in the drawing, the upper portion of the ignition plug is left uncovered, but if desired, it may be capped by means of any appropriate mounting, such as a lid, a cup or the like, which ought to be pierced with appropriate apertures to permit of cooling the center part of the ignition plug.

80 It is to be understood that the insulating member may be formed of any appropriate material such as molded mica, mica disks 85 or the like.

Having now particularly described and ascertained the nature of my said invention, and in what manner the same is to be performed, I declare that what I claim is:

90 1. An ignition plug comprising a seat or bottom, an insulating member fixed on said seat, a bored center rod fixed in the insulating member, said bored rod being open above, closed below by a thin bottom, having lateral apertures relatively large exclusively placed above the insulating member, the interior space of said bored rod being completely free.

95 2. An ignition plug, comprising a seat or bottom, an insulating member fixed on said seat, a bored center rod fixed in the

insulating member, said bored rod being open above, having lateral apertures relatively large exclusively placed above the insulating member and closed below by this bottom provided with a raised edge which is directed toward the exterior of the plug.

In testimony that I claim the foregoing

as my invention I have signed my name in presence of two subscribing witnesses.

LAVOISIER LUCIEN.

Witnesses:

CHARLES BAUDRY,
CHAS. P. PRESSLY.
